UNITED STATES PATENT OFFICE.

JOSEPH W. STEPHENS, OF DENVER, COLORADO.

COIN-RECEPTACLE.

SPECIFICATION forming part of Letters Patent No. 774,707, dated November 8, 1904.

Application filed February 8, 1904. Serial No. 192,653. (No model.)

To all whom it may concern:

Be it known that I, JOSEPH W. STEPHENS, a citizen of the United States of America, residing in the city and county of Denver and State 5 of Colorado, have invented certain new and useful Improvements in Coin-Receptacles; and I do declare the following to be a full, clear, and exact description of the invention, such as will enable others skilled in the art to which 10 it appertains to make and use the same, reference being had to the accompanying drawings, and to the letters of reference marked thereon, which form a part of this specification.

My invention relates to improvements in 15 coin-receptacles of the class adapted for use in connection with savings-banks. With these banks the practice is to loan each depositor one of these receptacles, and when he has filled it with coins or put in the desired quantity it 20 is brought to the bank and the amount deposited. Where this system is in vogue, the depositor is not supposed to have a key to the coin-receptacle or miniature safe, and it is important that the said receptacle, while permitting free access to coins, should be of such 25 construction that the coins cannot be removed except by unlocking and opening the safe, as is done at the savings-bank when the depositor returns the receptacle to the bank for that 30 purpose.

My object is to provide a device of this class 35 adapted to combine features of security against removal of the coins except by the authorized person holding the key with simplicity, and general efficiency so far as all the requirements in a device of this class are concerned.

Having defined the class to which my invention 40 belongs and outlined the objects I expect to attain thereby, I will proceed to describe the same in detail, reference being made to the accompanying drawings, in which is illustrated an embodiment thereof.

45 In the drawings, Figure 1 is a vertical longitudinal section taken through a coin-receptacle equipped with my improvements, showing a coin inserted in the chute and held therein preparatory to dropping it into the body 50 of the receptacle. Fig. 2 is a fragmentary

view of the same, showing the coin-chute adjusted to drop the coin into the body of the receptacle. Fig. 3 is a fragmentary underneath view of the lid or cover of the receptacle, showing the coin-chute in the position 55 shown in Fig. 1. Fig. 4 is a similar view showing the chute in the position shown in Fig. 2. Fig. 5 is a fragmentary top view of the receptacle with the lid removed. Fig. 6 is a section taken on the line 6 6, Fig. 5. 60

The same reference characters indicate the same parts in all the views.

Let A designate the body of the receptacle, which, as shown in the drawings, is stamped out of an integral piece of sheet-steel and 65 provided with rounded corners, thus preventing injury to polished articles of furniture with which it may come in contact and also making it smooth and easy to handle and, further, giving it a slight appearance. Secured 70 to one end of this receptacle is a ledge or plate A', which extends at right angles to the vertical wall of the receptacle and is rigidly connected therewith. As shown in the drawings, this ledge A' is formed integral with an 75 upwardly-projecting part A'', which is soldered to the wall of the receptacle or secured thereto in any other suitable manner.

Located below the rigid ledge A' is a plate 80 A³, hinged to the ledge A', as shown at A⁴. As shown in the drawings, the ledge A' is provided with ears A⁵, and the hinged plate A³ is provided with coöperating ears A⁶, and these two sets of ears are connected by hinge-pins A⁷, whereby the plate A³ is permitted a 85 limited degree of downward movement when the receptacle is in the upright position. The length of this plate A³ is somewhat greater than the ledge A', for reasons hereinafter explained. 90

The upper part of the body of the receptacle is provided on opposite sides at each end with lid-supporting ledges A⁸, which are supported or braced by beveled portions A⁹, which by reason of their inclination do not 95 obstruct the discharge of the coins from the receptacle after the lid has been removed. Also located at each end of the receptacle at the top is a narrow horizontal ledge A¹⁰. At one end of the receptacle this ledge is adapted 100

to catch two small lips B' , fast on one end of the lid B . These lips project slightly downwardly from the under surface of the lid, leaving sufficient space between them and the lid for the ledge A' to enter, while at the opposite end of the receptacle the narrow ledge A' is used to hold a locking-bolt B'' , connected with a lock B^3 , mounted on the lid, the said bolt being operated by a key B^4 .

10 It will be understood that any suitable locking mechanism may be employed in connection with my improved coin-receptacle. The lid B of this receptacle is provided with a transverse slot B^5 of sufficient length and 15 width to receive the largest coin which it is proposed to place therein or of the largest denomination of the currency of the country where the receptacle is used. At one side of this slot, being the side adjacent one end of 20 the receptacle, is a short slot B^6 , through which passes a stud B^7 , made fast to a cover-plate B^8 and also passing through a lip C' of the movable coin-chute C , which is movable on the lid to a degree equal to the length of 25 the slot B^6 . The lip C' is bent at right angles to the body of the chute, and the cover B^8 is connected with this lip by applying a nut to the lower extremity of the stud. The chute on the opposite side from the lip C' is also provided with another lip, (designated C^2), which is provided with a slot C^3 , through which is passed a screw C^4 , its upper extremity being threaded in the lid. The slot C^3 corresponds in length with the slot B^6 of the lid. The 30 chute is thus connected with the lid by means of the two lips C' and C^2 , and it is free to slide freely on the lid to cause its opening C^5 to register with the coin-slot B^5 or not, as may be desired. When the chute is in position to 35 register with the coin-slot B^5 , the coin-slot is open; but when the chute is moved to bring its upper extremity out of register or to the left of the coin-slot (see Fig. 2) the cover B^8 , connected with the chute, closes the coin-slot 40 against the entrance of coins. The coin-slot, as 45 shown in the drawings, is open at both ends and has closed walls. It is a narrow chute, but of sufficient size to receive the largest coin, or, in other words, is substantially of 50 the same area in cross-section as the coin-slot B^5 . When the opening C^5 of the chute registers with the slot B^5 of the lid, the opening at the lower end of the chute is directly above the ledge A' , so that a coin dropped into the 55 slot B^5 and entering the chute will rest upon the ledge A' . When the coin is in this position, it may be dropped into the body of the chute by moving the chute toward the left, referring to Figs. 1 and 2, sufficiently to 60 bring the opening at the lower extremity of the chute beyond or to the left of the outer extremity of the ledge A' . (See Fig. 2.)

The function of the hinge-plate A^3 is to prevent the removal of coins from the receptacle, and its length is such as to close the lower

extremity of the chute when the latter is in the position shown in Fig. 2. It is evident that in order to remove a coin from the receptacle the coin must first be made to enter the chute through its lower extremity. Hence 70 the receptacle must be inverted, and as soon as this occurs the hinge-plate drops over and closes the lower extremity of the chute and prevents the entrance of a coin.

One extremity of the receptacle—namely, 75 that remote from the coin-chute mechanism—is provided with an opening in which is inserted a short tube D , having its inner-edge toothed, as shown at D' . This opening and tube are to permit the insertion of paper currency. The object of the teeth is to prevent the removal of this species of currency, since paper will have a tendency to catch on the teeth. This, however, is not a novel feature in receptacles of this class and nothing is 85 claimed, broadly, thereon.

Having thus described my invention, what I claim is—

1. A coin-receptacle provided with a ledge rigidly secured to one wall thereof, the top of 90 the receptacle being provided with a coin-slot, an open-ended chute slidably mounted on the top of the receptacle to bring the opening of the chute into or out of register with the coin-slot, the ledge being of a length to close the 95 chute when in register with the slot but to leave it open when the chute is out of register with the slot, the chute having an exteriorly-located cover connected with the chute at one side of the body of the latter and slidably 100 therewith to close the slot when out of register with the chute and to open it when the chute and slot are in register, the ledge being of a length to close the inner extremity of the chute when the latter is in register with the 105 coin-slot and to leave the same extremity of the chute open when the coin-slot and chute are out of register.

2. A coin-receptacle provided with an open-ended chute movably mounted on one wall 110 thereof, the said wall being provided with a coin-slot, the range of movement of the chute being sufficient to bring the chute and slot into and out of register, one wall of the receptacle being provided with a ledge of a 115 length to close the inner extremity of the chute when the latter is in register with the coin-slot and leave it open when the slot and chute are out of register, and exteriorly-located means rigidly connected with the chute and 120 moving therewith to close the coin-slot when the chute is out of register therewith.

3. The combination of a coin-receptacle provided with a coin-slot formed in one of its walls, and a coin-chute located within the receptacle 125 and movable on the wall of the receptacle provided with a coin-slot, the chute having a degree of movement sufficient to bring it into or out of register with the coin-slot as desired, and a cover connected to move with the coin- 130

chute and exteriorly located on the side of the receptacle containing the coin-slot, the cover being located at one side of the body of the chute and arranged to close the coin-slot when 5 the chute is actuated to bring its body portion out of register with said slot.

4. The combination with a coin-receptacle, of a coin-chute slideable on one wall of the receptacle, the said wall being provided with a 10 coin-slot, and the chute being movable to bring it into and out of register with said slot, the chute being open at both ends, a ledge secured to the wall of the receptacle on the inside and of a length to project in front of the inner 15 extremity of the chute when the latter registers with the coin-slot, but leaving the inner extremity of the chute open when the latter is moved to bring it out of register with the coin-slot, and a hinged plate connected with 20 the wall of the receptacle adjacent the ledge and of greater length than the latter whereby it is adapted to close the inner extremity of the coin-chute when moved out of register with the coin-slot, the said plate being ar- 25 ranged to swing to and from the chute as described.

5. The combination with a coin-receptacle having a coin-slot in one wall thereof, a coin-chute slideable on the inner surface of the wall 30 of the receptacle containing the coin-slot and being movable to bring the chute into and out of register with the slot as desired, and an exteriorly-located cover rigidly connected with

the coin-chute and located at one side of the body portion of the chute for the purpose set 35 forth.

6. The combination with a coin-receptacle having a ledge on the inner surface of one of its walls, a removable lid adapted to close the receptacle on one side, said lid being provided 40 with a coin-slot, and having a coin-chute interiorly located and movably connected with its inner surface on the side containing the coin-slot, its degree of movement being such as to allow it to move into and out of register 45 with the coin-slot and having an exteriorly-projecting part movable with the chute and located at one side of the body portion of the chute, the ledge on the inner wall of the chute being of a length to close the inner extremity 50 of the latter when the chute registers with the coin-slot but leaving the said extremity of the chute open when the latter is moved out of register with the coin-slot, and a plate hinged to the receptacle on the inside adjacent the 55 ledge and somewhat longer than the latter whereby it is adapted to swing to close the inner extremity of the coin-chute when out of register with the coin-slot, substantially as described.

In testimony whereof I affix my signature in presence of two witnesses.

JOSEPH W. STEPHENS.
